Des. 1576

Henry A. Fowler, of Afton, N. Y.
Letters Patent No. 1576 dated May 13, 1862.

The schedule referred to in these Letters Patent and making part of the same.

To all whom it may concern:

Be it known that I, Henry A. Fowler of Afton, in the County of Shenango and State of New York, have invented or produced a new and original design for a Game fastening, and I do hereby declare that the following is a full, and exact description of the same, reference being had to the accompanying drawing, in which -

D is the main body of the design and is of an elongated form rounded at the corners as shown at $q, q.$ and having an elevated ridge L rising gradually from the points $n, n.$ to the points $e, e.$ where it is crowned by the ornamental cap $a, c, c.$ are hooks.

The whole forming a neat and ornamental design as shown.

What I claim as my invention and desire to secure by Letters Patent, is the ornamental design for a Game fastening as shown and described.

Witnesses.
